UNITED STATES PATENT OFFICE

105,883

DESIGN FOR A HANDBAG OR THE LIKE

Wing Yue Ma, Honolulu, Territory of Hawaii

Application May 21, 1937, Serial No. 69,475

Term of patent 14 years

To all whom it may concern:

Be it known that I, Wing Yue Ma, a citizen of China, residing at Honolulu, in the Territory of Hawaii, have invented a new, original, and ornamental Design for a Handbag or the like, of which the following is a specification, reference being had to the accompanying drawing, forming part thereof.

I claim:

The ornamental design for a handbag or the like, as shown.

WING YUE MA.
